UNITED STATES PATENT OFFICE.

RALPH BAGGALY, OF PITTSBURG, PENNSYLVANIA.

CAR-LOADING APPARATUS.

SPECIFICATION forming part of Letters Patent No. 746,250, dated December 8, 1903.

Application filed April 14, 1903. Serial No. 152,533. (No model.)

To all whom it may concern:

Be it known that I, RALPH BAGGALY, of Pittsburgh, Allegheny county, Pennsylvania, have invented a new and useful Car-Loading Apparatus, of which the following is a full, clear, and exact description, reference being had to the accompanying drawings, forming part of this specification, in which—

Figure 1 is an end view of my improved car-loading apparatus. Fig. 2 is a side elevation of the same, showing a box-car in dotted outline with the machine in position to load the car. Fig. 3 is a side elevation, on a larger scale, of the counting apparatus which I employ at the delivery end of the chute, which receives the pigs or other articles from the conveyer and delivers them into the loading apparatus. Fig. 4 is a plan view on the same scale as Figs. 1 and 2, showing the car in dotted lines. Fig. 5 is an enlarged cross-section on the line V V of Fig. 4, showing the distributing-arm. Fig. 6 is an enlarged cross-section on the line VI VI, showing the construction of the curved chute by which the pigs or other articles are delivered to the distributing-arms. Fig. 7 is a plan view of one of the distributing-arms; and Fig. 8 is a side elevation of the same, partly broken away to show its internal construction more clearly.

30 My invention relates to a loading apparatus for receiving pigs of copper and other like articles from a storage-warehouse or other suitable source of supply and delivering them for shipment into box-cars or other vehicles without the necessity of employing manual labor.

This loading apparatus is preferably a part of a complete system for treating copper or other ores and storing and handling the same when cast into pigs or like articles, although it may be used independently thereof to advantage, since by its use manual labor is practically dispensed with and the pigs or other articles are evenly and automatically distributed upon the floor of the car or other vehicle.

50 The pigs of refined copper after having been cast are weighed, marked, and stored in suitable racks of an automatic warehousing-machine, beneath which runs a conveyer upon which the pigs or other articles are deposited and by which they are carried to the loading

apparatus, which forms the subject-matter of this application. As each pig is delivered to the loading-machine it actuates mechanism 55 by which when the requisite number of pigs have been received and loaded an alarm will be given. In order to simplify the construction, the pigs are preferably delivered to the loading apparatus by the conveyer from the 60 warehouse at a sufficient elevation to enable the distribution to be effected by gravity, and by their own movement are automatically deposited upon the car-floor in proper quantities and in the proper location. About three 65 hundred pigs of two hundred pounds each constitute a car-load and are loaded with one-half the number at each end of the car, the pigs being shunted to the desired end by a 70 tilting trough-section centrally located with respect to the curved delivery-chutes.

Referring to the accompanying drawings, 2 represents a conveyer which leads from a warehousing-machine or other suitable source of supply of pigs of metal.

75 3 is a chute provided with a registering device. This comprises an arm 4, mounted on a shaft 5 and provided with an arm 6, to which is secured a spring 7 and a pawl 8, which engages a ratchet-wheel 9, having upon its 80 shaft 9' a pinion 10, which meshes with a larger toothed wheel 10', which is provided with a pin or projection 11, which at one point in its rotation engages an arm 12, mounted on a rock-shaft 13, to which is secured an 85 arm 14, having a rod-link connection 15 with a hook or detent 16, pivoted to the under side of a tilting trough-section 17 and arranged to engage a bracket 18. The tilting trough-section 17 is also provided with a rod 19, which 90 preferably extends downwardly to a convenient point so that the operator may use it to set the trough in the position shown in dotted lines in Fig. 2. A spring 17' is employed to automatically tip the trough when the hook 95 or detent is released by the pin 11 engaging the arm 12 when the last pig sufficient to complete the consignment has been received.

This movement of the arms 12 and 13 also actuates a cord or chain 20 and operates an 100 alarm-whistle or other signal, which notifies the proper person that the car is loaded to full capacity or for any other purpose that may be desired. The tipping trough-section

17 is pivotally mounted upon a suitable framework and when in the position shown in full lines in Fig. 2 will deliver a succession of pigs to the left-hand end of the car. A pair of stationary chute-sections 22, preferably spirally curved and inclined downwardly, as shown in Figs. 1 and 2, are secured to a suitable framework, and one end is provided with a flanged connection 22', by which it is 5 united to a similar flange upon the upper end of the movable delivery end of the spiral inclined chute 23, by which the pigs are delivered to the distributing-arms 24, supported by hangers 25 from trolleys 26, which may be 10 moved in and out of the car if it be a box-car through the doors or into and out of position for distribution if the car be a flat-car or other vehicle. The trolley 26 is mounted upon rails 27, supported upon suitable beams. 15 The end 28 of the distributing-arm 24 is preferably made heavy, so as to act as a counter-weight for the opposite longer end of the arm. The end of the distributing-arm in front of the chute 23 is preferably somewhat inclined 20 downwardly, and the interior of the arm is provided with antifriction-rollers 29, Fig. 5, spaced at suitable intervals and supported by angles 30, secured to the side plates of the arm 24. Guiding-bars 31 for the pigs are also provided, as shown in Fig. 5. As the pigs B slide over the rollers 29 and between the guides 31 they pass under an arm 32, secured to a rock-shaft 33, having an arm 34, a link 35 connecting it to an arm 36 on a rock-shaft 37, Fig. 8, upon the opposite end of which is secured an upwardly-extending arm 38, to which a pawl 39 is secured. This pawl 39 moves the ratchet-wheel 40 one tooth for each pig that passes under the arm 32, and 40 after a predetermined number of pigs have passed over the outer end of the arm 24 a pin or projection 41 engages an arm or finger 42, secured to the arm 43, and through the rod 44 operates the arm 45, which actuates the hook 46, which is secured to the same shaft as the arm 45. The hook 46 engages a rod 46', which extends between the arms 47, which are pivoted to the frame of the arms 24 at 47'. To the free end of the arms 47 are 45 secured links 48, which support a pivoted section 49, which forms a drop-bottom when the hooks 46 are disengaged from the rods 46', as shown in dotted lines in Fig. 8. When the pivoted section 49 is dropped, the next 50 series of pigs are discharged through this opening, and after a predetermined number have been so distributed the pin 41 engages a similar finger, which operates link and lever connections which are like those just described, and the next pivoted section 50 is 55 dropped. This is repeated until the pivoted sections 51, 52, and 53 have been thus operated and the pigs distributed automatically and evenly upon the car-floor at the end of the car. In this manner in a total car-load of three hundred pigs twenty-five are first delivered in a pile out of the end of the chute. 60

The ratchet mechanism by the passage of the first twenty-five pigs will then open door 49, so that the second twenty-five pigs will be delivered in another pile nearer the center of the car. When fifty pigs have thus passed, the second door 50 will have been opened and a third pile of twenty-five pigs will be so deposited still nearer the center of the car. In like manner doors 51, 52, and 53 will be opened in regular sequence, and through each such door similar piles consisting of twenty-five pigs each will be deposited each in succession nearer to the center of the car. Thus one hundred and fifty pigs, or one-half of a car-load, will be automatically deposited in six even piles of twenty-five pigs each diagonally across the floor of one-half of the car. When this point has been reached, the ratchet mechanism then shifts or tilts the platform 17, (shown in Fig. 3,) and in like manner the next succeeding one hundred and fifty pigs will be deposited through the other door of the car and onto or over the other half of the floor of such car and diagonally across the same in six evenly-distributed piles of twenty-five pigs each. It will therefore be apparent that when the car has thus automatically received its entire load—consisting, for instance, of three hundred pigs—such load will be evenly distributed and properly balanced over the entire floor-surface of such car in twelve piles consisting of twenty-five pigs each, or approximately sixty thousand pounds. This tonnage constitutes the ordinary car-load in shipping copper. Hence it is quoted here simply as an illustration. Any other desired tonnage may be so delivered automatically over the floor-space of a railroad-car or elsewhere by a simple arrangement of the ratchet mechanism so that it will produce the desired result. A tally having been kept, the operator pulls the rod 19, tilts the trough 17, and the next series of pigs are delivered in like manner to the opposite end of the car. As the last pig for the car-load or consignment is delivered to the loading apparatus the alarm-whistle is blown and the tilting trough is tipped into the position shown in Fig. 2. The arms 24 are then moved out of the way, as shown in dotted lines in Fig. 4, the joint 22' being first disconnected to permit this to be done. The loaded car may then be moved out of the way and an empty car moved into position, after which the arms are projected through the door-opening of the cars if a box-car is to be loaded and the curved chutes are attached together at 22' and the loading of the car proceeded with, as already described. 110

By the use of this apparatus the cars may be loaded rapidly, pigs may be placed upon the floor of the car in the proper position, the distribution being automatically provided for, and the position of the distributing or delivering arms, being maintained above the level of the pig or other articles delivered to the car, does not interfere with the free withdrawal 130

of the arms when the loading of the consignment of pigs is completed.

The pivoted sections 49 50 51, &c., Fig. 8, are shown in the drawings as being reset by hand; but, if desired, automatic means may be provided to return them to their closed or raised position.

The advantages of my invention will be apparent to those familiar with the difficulties experienced in the handling of metal pigs and like articles, since by the use of this apparatus much time and labor are saved, and the apparatus being simple in construction is reliable and not likely to get out of order and when not in use may be moved out of the way, so that no obstruction is afforded to the movement of the cars into and out of position.

Many variations in the mechanical construction of this device will suggest themselves to the skilled mechanic, and changes in the form and arrangement of the parts may be made without departing from my invention.

I claim—

1. A loading device for cars having a distributor adapted to extend over the car-floor, and adapted to deliver articles thereto, and means actuated by passage of the articles and adapted to discharge the articles at various parts of the distributor; substantially as described.

2. A loading device for cars having a distributor adapted to extend over the car-floor, and means for discharging the articles at various parts of the distributor, said distributor having two arms extending over the car-floor in opposite directions; substantially as described.

3. A loading device for cars having a distributor adapted to extend over the car-floor, and adapted to deliver articles thereto, said distributor having movable sections actuated by passage of the articles, and adapted to open and discharge the articles at various parts of the distributor; substantially as described.

4. A loading device for cars having an elevated source of supply, a chute, and a distributor adapted to receive articles from said elevated source of supply, said distributor being adapted to extend over the car-floor, and means for discharging the articles at va-

rious parts of the distributor, said distributor having two arms extending over the car-floor in opposite directions; substantially as described.

5. A loading device for cars having two arms extending in opposite directions over the car-floor, an elevated source of supply, chutes extending from said elevated source of supply to said distributing-arms, a switch located at the junction-point of said chutes, and mechanism by which said switch is operated to cause the pigs or other articles to be discharged into the distributing-arm, according to the deflection given the article by the position of said switch; substantially as described.

6. A loading device for cars having a distributing-arm arranged to extend above the floor of the car, openings in the bottom portion of said arm provided with closing devices, and mechanism arranged to automatically release said closing devices; substantially as described.

7. A loading device for cars having a downwardly-inclined distributing-arm provided with antifriction-rollers arranged to extend above the floor of the car, openings in the bottom portion of said arm provided with closing devices, and mechanism arranged to automatically release said closing devices; substantially as described.

8. A loading device for cars arranged to receive and distribute metal pigs and the like upon the floor of the car, having a distributing-arm arranged to extend above the floor of the car, openings in the bottom portion of said arm provided with closing devices, and mechanism arranged to automatically release said closing devices when engaged by the pig or other article as it passes along said arm toward the discharging end thereof, said closing devices being successively released at predetermined intervals; substantially as described.

In testimony whereof I have hereunto set my hand.

RALPH BAGGLEY.
